UNITED STATES PATENT OFFICE.

WILLIAM EUGENE ENDREZZE, OF BUTTE, MONTANA.

ORE CLASSIFIER.

Application filed September 17, 1927. Serial No. 220,122.

This invention appertains to ore classifiers and has for its prime object to generally improve upon similar structures now well known in the art to provide a more efficient and reliable operation in the separating and classifying of materials which have different settling rates in liquid, whether such difference is caused by a variation in the specific gravity of the particles, as in 10 the concentration of ores, or in the size of the particles when homogeneous as in the separation of sand and slimes.

The apparatus, however, is exemplified in the present application as being designed 15 particularly for classifying the sands and slimes in wet crushed pulp for cyaniding and for convenience it will be assumed in the following description that the pulp is being treated for that purpose.

20 A further important object of the invention resides in the provision of an ore classifier of this nature which is particularly simple in its construction, not likely to easily become out of order when in operation, and 25 otherwise well adapted to the purpose for which it is designed.

With the above and numerous other objects in view as will appear as the description proceeds, the invention resides in certain 30 novel features of construction, and in the combination and arrangement of parts as will be hereinafter more fully described and claimed.

In the drawing:-

35 Figure 1 is a side elevation of an ore classifier embodying the features of my invention,

Figure 2 is an end elevation thereof,

40 Figure 3 is a vertical transverse section taken substantially on the line 3-3 of Figure 1,

Figure 4 is a top plan view with the conveyor removed,

45 Figure 5 is a vertical longitudinal section taken substantially on the line 5-5 of Figure 4,

Figure 6 is a top plan view of another embodiment of the invention showing a double trough with the conveyors removed,

50 Figure 7 is a vertical transverse section therethrough taken substantially on the line 7-7 of Figure 6, and,

Figure 8 is an end elevation of the lower end of the trough structure.

Referring to the drawings in detail and particularly the embodiment of the invention shown in Figures 1 to 5 inclusive, it will be seen that the tank 5 forms an elongated trough which is disposed at an incline, being suitably mounted in a frame 5 supporting structure 6 which is also inclined, one end of which may rest on the ground and the other end of which may be supported in elevation by a standard structure 7, or in any other suitable manner.

On the upper edge of the lower end wall and the adjacent side walls there is provided a launder structure 8 for receiving slimes, the side branches of this launder structure being particularly well illustrated in Figure 4, and in one corner thereof is a drain or outlet pipe 9.

Intermediate the ends of the bottom of the trough forming tank 5 there is an oblong opening 10 covered by screening or other foraminous sheet material 11. A box-like casing 12 is supported below the opening 10 and the screen 11 and has nipples 13 and 14 depending therefrom in alternate relationship to feed air and water thereto respectively. An outlet 15 depends from the upper end of the bottom.

A shaft 16 is journaled longitudinally in the trough forming tank 5 through the upper and lower walls thereof, the lower end being journaled in a bearing structure 17 mounted

85 on a cross member 18 of the frame 6, while the upper end of the shaft is journaled in a bearing 19 on the cross member 20 of the frame structure 6. A beveled gear 21 is mounted on the shaft 16 adjacent the bearing 17 and meshes with a beveled pinion 22

90 operatively connected with a pulley 23 which may be belt or otherwise driven for setting up rotation to the shaft 16. A spiral conveyor and agitating structure 24 is

95 formed coaxially on the shaft 16 so that the major portion thereof is completely submerged when the tank is filled as much as possible with the fluid.

The embodiment of the invention shown 100 in Figures 6, 7 and 8 is practically identical with that just described, except that the bottom of the particular tank 5' illustrated in these figures is transversely curved to pro-

vide two troughs A and B. Each of these troughs is otherwise identical with the single trough structure as to the shaft, bearings, and the like. The drive means, however, is duplicated as is clearly illustrated in Figure 6. It is also preferable to have the slime launder with its outlet 9' at the center and the bottom of this launder inclined thereto.

- 10 A classifier tank embodying the features of this invention operates efficiently and in a reliable manner because of the rotating spiral sand conveyor structure mounted therein. This spiral rotating within the 15 classifier tank acts upon settled sands at the bottom of the trough or troughs and conveys said sands forwardly and upwardly along the inclined bottom or bottoms of the trough or troughs, and to a chute 20 or outlet where the sands are dumped. While this action is taking place, the slimes that have been separated from the sands flow out of the classifier tank at the lower end into the side and back launder structures for conveying off the slime to suitable 25 receptacles or the like. Classification is obtained by the action of water upon the slimes and by action of gravity upon the sands and coarser particles, the difference 30 of settling rate of particles contained within the tank. The sand is agitated and washed by the admixture of the air and water through the box structure 12 and the screening 11.
- 35 A classifier tank embodying these features enables the lower end of the spiral conveyor to be completely submerged. This allows the depth of the settling tank to be increased considerably over analogous 40 structures and the increasing of the depth of the settling tank allows the particles of crushed pulp and ore varying in size and settling rate to take their position at a certain level within the tank. This increasing 45 of the depth of the tank also allows of a larger tonnage to be handled by the same size classifier. This structure also provides a more dense overflow of slime, particularly because of the increased capacity and the 50 submerging of the spiral completely allows the slimes to leave the tank more freely, it being noted that the spiral does not disturb the action of classification in the upper stratum of the bath. The submerging 55 of the lower end of the spiral conveyor washes the flights free of any sands that have adhered to them. This feature of submerging the spiral conveyor also prevents any sand or coarse particles from getting 60 into the overflow as the spiral rotating in the sands at the bottom of the tank has a tendency to pick up the sands at certain places and carry them upwardly to a position where they drop off and fall to the bottom of the tank by having the level of the

liquid above the spiral, these sands have absolutely no chance to go into the overflow and destroy the results of classification and this is pointed out as a very vital feature of this invention. This elimination of the 70 tendency of the sands to mix with the overflow allows the machine to be fed more heavily without destroying its classification, and allows the level of the pulp to be above the spiral which permits the side launders 75 to be placed at a very convenient and effective position for receiving the slimes discharged from the tank. These side launders tend to spread the slimes flowing out of the tank at a greater area thereby reducing the 80 tendency to form a current toward the back end of the tank. This type of tank allows the feed to be admitted at a more convenient position and allows of a more effective control of the pulp for the classification of 85 slimes and sands contained therein.

It is thought that the construction, operation, utility, and advantages of the invention will now be clearly understood by those skilled in this art without a more detailed 90 description thereof. The present embodiments of the invention have been disclosed in detail merely by way of example since in actual practice they attain the features of advantage enumerated as desirable in the 95 statement of the invention and the above description.

It will be apparent that changes in the details of construction, and in the combination and arrangement of parts may be resorted to without departing from the spirit 100 or scope of the invention or sacrificing any of its advantages.

Having thus described my invention, what I claim as new is:—

1. An apparatus for classifying crushed ore comprising a stationary inclined trough through which the material to be separated moves, said trough being open at its top and formed with a transversely curved bottom, a spiral conveyor, means for journaling the spiral conveyor longitudinally in the trough in substantial parallelism therewith, so that the periphery of said spiral will operate in close relation with the bottom of the trough, a slime receiving launder structure across the end of the trough, and means for forcing liquid and air up through the bottom of said trough intermediate the ends thereof to separate the slimes from the sand contents, and means for discharging the settled sand from the trough. 105 110 115 120

2. An apparatus for classifying crushed ore comprising a stationary inclined trough through which the materials to be separated pass, said trough being open at its top and formed with a transversely curved bottom, a spiral conveyor, means for journaling the spiral conveyor longitudinally in the trough in substantial parallelism therewith so that 125 130

the periphery thereof will operate in close disposition with the curved bottom thereof, the top edges of said trough at its lower end portion being disposed longitudinally to increase the depth of the trough at this point, a weir constructed within the lower end of the trough and provided with an outlet through which the slimes from the tank flow, and means for forcing liquid and air up through the bottom of said trough intermediate the ends of the same to separate the slimes from the sand content, and means for discharging the settled sand from the trough. In testimony whereof I affix my signature.

WILLIAM EUGENE ENDREZZE.
